Primary Examiner — Cynthia Ramirez*Assistant Examiner* — Gino Colan(57) **CLAIM**

The ornamental design for a column pump, as shown and described.

DESCRIPTION

FIG. 1 is a first perspective view of a column pump showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 2.

The broken lines in the drawings illustrate portions of the column pump which form no part of the claimed design.
